UNITED STATES PATENT OFFICE.

ALBUERTO BEMENT, OF CHICAGO, ILLINOIS.

HUMIDIFYING DEVICE.

1,182,625.

Specification of Letters Patent. Patented May 9, 1916.

Application filed June 7, 1915. Serial No. 32,591.

To all whom it may concern:

Be it known that I, ALBUERTO BEMENT, a citizen of the United States, residing at Chicago, in the county of Cook and State of Illinois, have invented certain new and useful Improvements in Humidifying Devices, of which the following is a specification.

My invention relates to means for introducing moisture into the atmosphere of a room or other inclosure, and the principal object of the invention is to provide a device for injecting steam into the atmosphere from the steam containing means such as a radiator or steam supply pipe, which device will operate silently and without sputtering or discharging water. In a living room a humidifying device which operates noisily is extremely objectionable. It is equally objectionable to have the device sputter water because of the likelihood of carpets, furniture, and the like being injured thereby.

The invention consists in the novel constructions, arrangements and devices to be hereinafter described and claimed for carrying out the above objects and such other subordinate objects as will appear from the following specification.

The invention is illustrated in the accompanying drawings, wherein—

Figure 1 shows, in elevation, a radiator with a humidifying device constructed in accordance with my invention attached directly thereto. Fig. 2 is a vertical section, on a larger scale, of the humidifying device and the adjacent portion of the radiator. Fig. 3 is a sectional view taken on line 3—3 of Fig. 2. Fig. 4 is a view, similar to Fig. 1, illustrating a modification intended particularly for attachment to a horizontal pipe, for example the inlet pipe of the radiator. Fig. 5 is an enlarged sectional view of the device, and Fig. 6 is a sectional plan taken on line 6—6 of Fig. 5.

Like characters of reference designate like parts in the several figures of the drawings.

Referring first to Figs. 1 to 4 inclusive, 10 designates an outer shell provided with a threaded nipple 11 for attachment to one of the sections 12 of a radiator. The shell 10 is closed at the bottom by a head 13 formed with an internally threaded boss 14 which supports a smaller head or web 15 and terminates above this head in a nozzle 16. The upper head 15 is formed with a

duct 17 communicating with a pipe 18 which extends through nipple 11 into the radiator. A valve 19 formed on the end of a threaded stem 20 which passes through the boss 14, is adapted to shut off communication between duct 17 and the nozzle 16. The valve stem has a handle 21. 22 is a packing nut on the lower end of the boss 13. 23 is an inner shell mounted on the smaller head 15. Within the inner shell 23 is a retarding and silencing element consisting preferably of two cylinders 24, 25, made of fine wire mesh between which is arranged a body of asbestos 26. The cylinder is closed at the bottom by a disk 27. Its upper end is open and fits over a discharge pipe 28. The space around the silencing element is closed at the top by an annular member 29. The space between the inner and outer shells constitutes a steam jacket 30 communicating with the radiator through nipple 11, the steam in which serves to prevent the condensation of the steam in the chamber 31, within the inner shell 23, in which the retarding and silencing element is located. The discharge pipe is surrounded by a tubular member 32 connected to the shell 10 by an annular member 33. The extension of the steam jacket thus formed is closed at the top by a ring 34.

In the form of the invention shown in Figs. 1 to 3 inclusive I have shown the steam jacket as provided with an air vent adapted to be closed after the air has been forced from the jacket by means of a thermostatically operated valve. Secured to the tubular member 32 is a small pipe 33 which communicates with the steam jacket through openings 34. In the upper end of pipe 33 is a valve seat 35, preferably having a threaded connection with the pipe 33 for adjustment. Within pipe 33 is an expandable element 36 having a valve 37 at its upper end. The valve 37 stands open to allow the escape of air until the incoming steam reaches and expands the member 36, whereupon the air vent 38 in the valve seating member 35 is closed.

Operation: With valve 19 open, steam enters the chamber 31 through pipe 18 and nozzle 16. If the device is cold some condensation will necessarily take place. The water of condensation, however, collects in the pocket 38 formed in the lower part of chamber 31, and remains there until the device has become heated when it is vapor-

ized. The steam from nozzle 16 does not come in contact with the water of condensation in the pocket, if any there be, so that the presence of water in the device does not cause sputter or interfere with the proper operation of the device as would be the case if the water were in the path of the steam. The steam passes from chamber 31 through the retarding and silencing element 24, 25, 26 and thence directly to the atmosphere through the discharge pipe 28. The steam is wire drawn and superheated in passing through the silencer so that it is discharged in dry condition. The discharge pipe is kept hot, as well as the inner shell 23, by the steam jacket 30 so that after the device has once become heated up there is no condensation formed anywhere to prevent the intended and proper operation. The steam is delivered into the room in dry condition. It will be observed that the pipe 18 extends quite a little distance beyond the nipple 11. The latter provides not only for ingress of steam to the steam jacket but also affords a passageway for the escape of water of condensation therefrom. If the pipe 18 through which steam is introduced to the silencing element terminated near the nipple the steam entering the pipe might draw with it some of the water of condensation outflowing through the nipple. The function of the thermostatically controlled air valve is to permit the escape of air from the jacket when steam is first turned on; otherwise, the jacket will become air bound.

In Figs. 4 to 6 inclusive, the device is modified slightly in its construction so that it may be placed upon a horizontally extending pipe, for example, upon the supply pipe 39 of the radiator 40. In this position the humidification of the room does not depend upon steam being turned on in the radiator. The upper part of the device is exactly the same as that shown in the preceding four figures and the parts are correspondingly numbered except that as shown and claimed in my co-pending application Serial No. 816,047, filed February 2, 1914, the steam jacket is provided with an air drain pipe 35 instead of the thermostatic valve shown in the preceding figures herein. Furthermore, in the modified construction the outer shell 10' is mounted upon the head 41 of a nipple 42 which is screwed into pipe 39. Set into and secured to one side of the outer shell 10' is a casting 43 formed with a valve chamber 44, a duct 45 with which the air pipe 35 is connected, and a communicating duct 46 to which leads a pipe 47 extending from the interior of the radiator through nipple 42. The casting 43 is formed with a steam nozzle 48 which opens out of the valve chamber 44. 49 is a gland for the stem 50 of a valve 51, which

latter is adapted to shut off communication between the duct 45 and valve chamber 44. 52 is a packing nut on the end of gland 49.

The operation of the device just described is the same as that of the previously described embodiment of the invention.

It will be understood that I do not intend to limit the invention to the particular construction, arrangements and devices shown and described except so far as expressed in the appended claims.

This application is a continuation in part of my co-pending application Serial No. 816,047, filed February 2, 1914, the claims generic to the form of the invention shown in said application and to both forms of the invention shown herein having been placed in this case in order to maintain a proper line of division between said applications.

I claim:

1. A humidifying device for introducing steam from a source of supply into the atmosphere provided with a retarding and silencing element permeable to steam, a discharge duct through which the steam from said silencing element passes immediately to the atmosphere, a steam jacket surrounding said duct, and separate steam passageways leading from the source of supply to the silencing element and jacket, respectively.

2. A humidifying device for introducing steam from a source of supply into the atmosphere formed with a chamber in communication with said source of supply of steam, a hollow retarding and silencing element arranged in said chamber, a discharge duct leading from the interior of the silencing element immediately to the atmosphere, and a jacket surrounding said chamber and duct and means providing an air vent for said jacket.

3. A humidifying device for introducing steam from a source of supply into the atmosphere formed with a chamber in communication with said source of supply of steam, a hollow retarding and silencing element arranged in said chamber, a discharge duct leading from the interior of the silencing element immediately to the atmosphere, and a jacket surrounding said chamber and duct provided with an inlet passageway separate from that leading to said chamber.

4. A humidifying device for introducing steam from a source of supply into the atmosphere having a chamber provided with an inlet duct communicating with said source of supply, a retarding and silencing element through which steam passes from said chamber to the atmosphere, said chamber being formed with a pocket to collect water of condensation below the level of said inlet duct, and a steam jacket surrounding said chamber having an inlet duct communicating with said source of supply separate from the inlet duct leading to said chamber.

5. A humidifying device for introducing steam from a source of supply into the atmosphere comprising a chamber communicating with said source of supply, a steam jacket having separate communication with the source of supply surrounding said chamber, formed with an air vent, a valve to close the same and a member which expands at the temperature of steam for seat-
10 ing the valve.

6. In a humidifying device, the combination of an outer casing, an inner casing, separate heads closing the adjacent ends of said casings, a nipple for supporting the device on a radiator or the like, which provides means of communication between the radiator and the space within the outer casing, means providing a separate steam duct extending through said nipple into the space
20 within the inner casing, a hollow silencing element permeable to steam within the inner casing, the end of which adjacent the head of said casing is closed and the other end open, a discharge pipe providing an unob-
25 structed passageway to the atmosphere for the steam which passes through said silencing element, and a casing element surrounding said discharge pipe which with the aforesaid outer casing provides a steam
30 jacket for the inner casing and discharge pipe.

7. In a humidifying device, the combination of an outer casing, an inner casing, separate heads closing the adjacent ends of
35 said casing, a nipple for supporting the device on a radiator or the like, which provides means of communication between the radiator and the space within the outer casing, means providing a separate steam duct
40 extending into the space within the inner casing above the head thereof, a hollow silencing element permeable to steam within the inner casing, the end of which adjacent the head of said casing is closed and the
45 other end open, a discharge pipe providing an unobstructed passageway to the atmosphere for the steam which passes through said silencing element, and a casing element surrounding said discharge pipe which with
50 the aforesaid outer casing provides a steam jacket for the inner casing and discharge pipe.

8. A humidifying device for introducing steam from a source of supply into the atmosphere comprising an inner shell having an inlet port communicating with said source of supply of steam at one end and
55 open directly to the atmosphere at the other, a retarding and silencing element in the
60 end of the chamber adjacent said inlet port and arranged so that the steam is compelled to pass therethrough in order to escape from the open end of the shell, and an outer shell which surrounds the inner shell for its en-
65 tire length and communicates with said

source of supply through a duct separate from the steam duct leading to the inner shell.

9. In a humidifying device, the combination with a fitting having a nipple for attaching it to a radiator or the like, and formed with a steam port, of a hollow element secured to said fitting into which said steam port leads, a hollow silencing body permeable to steam which is arranged in
75 said hollow element and opens directly to the atmosphere at one end, an outer casing surrounding said hollow element so as to provide a steam jacket therefor which is in constant communication with the interior of
80 the fitting, and a valve to control the flow of steam through said steam port.

10. In a humidifying device, the combination with a fitting having a nipple for attaching it to a radiator or the like, and formed with a steam port, of a hollow element secured to said fitting into which said steam port discharges, a hollow silencing body permeable to steam which is arranged in said hollow element and is open to the atmosphere at one end, an outer casing surrounding said hollow element so as to provide a steam jacket therefor which is in constant communication with the interior
90 of the fitting, a valve to control the flow of steam through said steam port, and a pipe extending through said nipple to said steam port.

11. A humidifying device comprising a hollow element and formed with a steam port leading into said hollow element, a pair of hollow members formed of wire mesh and arranged one within the other in said hollow element, and a body of asbestos between said hollow members, said structure formed by the wire mesh and asbestos being open to the atmosphere at one end for the purpose of discharging the steam which passes therethrough.

12. A humidifying device comprising a hollow element and formed with a steam port leading into said hollow element, a pair of hollow members formed of wire mesh and arranged one within the other in said hollow element, a body of asbestos between said hollow members, said structure formed by the wire mesh and asbestos being open to the atmosphere at one end for the purpose of discharging the steam which passes therethrough, and means constituting
110 a steam jacket surrounding said hollow element.

13. A humidifying device comprising a chamber having an intake port adapted to communicate directly with a source of supply of steam, a silencing element, permeable to steam, arranged so that steam from said chamber passes therethrough directly to the atmosphere, and a steam jacket surrounding said chamber, having an intake port in-
120 125 130

dependent from the intake port of said chamber.

14. A humidifying device comprising a fitting adapted to be attached to a radiator or the like and having a steam intake port, means associated with said fitting constituting a chamber and a steam jacket surrounding the chamber, the latter being in direct communication with the interior of said fitting, an intake pipe separate from said intake port which leads to the chamber through said fitting and extends into the radiator beyond the fitting, and a silencing element permeable to steam, arranged so that the steam from said chamber passes therethrough to the atmosphere.

15. In a humidifying device for discharging steam from steam containing means into the atmosphere, the combination of a steam permeable body of silencing material through which steam passes from the containing means to the atmosphere, and a structure which completely incloses said body so as to protect the same from contact with the outside atmosphere; said device being formed with a discharge orifice opening unobstructedly to the atmosphere and with a steam jacket which maintains the steam passing through the device in a heated state.

30 16. In a humidifying device for discharging steam from steam containing means into the atmosphere, the combination of a steam permeable body of silencing material through which steam passes from the containing means to the atmosphere, and a structure which completely incloses said body so as to protect the same from contact with the outside atmosphere; said device being formed with a discharge passageway opening unobstructedly to the atmosphere, and with a steam jacket which surrounds said silencing body and passageway to maintain the steam passing through the device in a heated state.

45 17. In a humidifying device for discharging steam from steam containing means into the atmosphere, the combination of a steam permeable body of silencing material in unobstructed communication with the steam containing means through which the steam passes from said containing means to the atmosphere, and a structure which completely incloses said body so as to protect the same from contact with the outside atmosphere, said device being formed with a discharge orifice opening unobstructedly to the atmosphere, and with a steam jacket which maintains the steam passing through the device in a heated state.

60 18. In a humidifying device for discharging steam from steam containing means into the atmosphere, the combination of a hollow steam permeable body of silencing material through which steam passes from outside to inside and which is open unobstructedly

to the atmosphere at one end, and a structure which completely incloses said body so as to protect the same from contact with the outside atmosphere, said device comprising a steam jacket to maintain the steam passing through the device in a heated state.

19. In a humidifying device for discharging steam from steam containing means into the atmosphere, the combination of a steam permeable body of silencing material through which steam passes from the containing means to the atmosphere, and a structure which completely incloses said body so as to protect the same from contact with the outside atmosphere, said device being formed with a steam inlet duct leading to said body, a steam discharge orifice opening unobstructedly to the atmosphere, a steam jacket which maintains the steam passing through the device in a heated state, and a duct through which water of condensation from the jacket is delivered back to the containing means at a point remote from the inlet end of the inlet duct.

20. In a humidifying device for discharging steam from steam containing means into the atmosphere, the combination of a steam permeable body of silencing material through which steam passes from the containing means to the atmosphere, and a structure which completely incloses said body so as to protect the same from contact with the outside atmosphere, said device being formed with a steam inlet duct leading to said body, a steam discharge orifice opening unobstructedly to the atmosphere, a steam jacket which maintains the steam passing through the device in a heated state, and a duct through which steam is supplied to the jacket and water of condensation is delivered therefrom to the containing means at a point remote from the inlet end of said inlet duct.

21. In a humidifying device for discharging steam from steam containing means into the atmosphere, the combination of a steam permeable body of silencing material through which steam passes from the containing means to the atmosphere, and a structure which completely incloses said body so as to protect the same from contact with the outside atmosphere, said device being formed with a steam inlet duct leading to said body, a steam discharge orifice opening unobstructedly to the atmosphere, a steam jacket which maintains the steam passing through the device in a heated state, and a duct through which water of condensation is delivered back to the containing means, the steam inlet duct comprising a pipe which extends through said last mentioned duct and beyond the same into the containing means.

22. In a humidifying device for discharging steam from steam containing means into the atmosphere, the combination of a steam

permeable body of silencing material through which the steam passes from the containing means to the atmosphere, and a structure which completely incloses said body so as to 5 protect the same from contact with the outside atmosphere, said device being formed with a discharge orifice opening unobstructedly to the atmosphere and with a steam jacket in communication at one end 10 with said steam containing means and provided at the other with an air vent.

23. In a humidifying device for discharging steam from steam containing means into the atmosphere, the combination of a steam 15 permeable body of silencing material through which steam passes from the containing means to the atmosphere, a structure which

completely incloses said body so as to protect the same from contact with the outside atmosphere; said device being formed with 20 a discharge orifice opening unobstructedly to the atmosphere and with a steam jacket which maintains the steam passing through the device in a heated state, and means adjacent said steam permeable body and inclosed by said steam jacket providing a 25 pocket located out of the path of the steam through the device for collecting and evaporating water of condensation.
